UNITED STATES PATENT OFFICE

2,375,192

HOSPITAL BED

Albert L. Bresch, University City, Mo.

Application February 28, 1942, Serial No. 432,729

7 Claims. (Cl. 5—83)

This invention relates to a certain new and useful improvement in hospital beds and has for its chief object the provision of an attachment whereby a hospital bed may be economically equipped with readily actuatable means for easily and conveniently either raising or longitudinally shifting, or both raising and longitudinally shifting, the patient, invalid, or other occupant with respect to the bed proper as may be required or desirable either for his or her comfort, for facilitating movement or handling of the occupant during illness, or for other reasons or causes whatsoever.

And with the above and other objects in view, my invention resides in the novel features of form, construction, arrangement, and combination of parts presently described and pointed out in the claims.

In the accompanying drawings (two sheets)—

Figure 1 is a plan view of a hospital bed equipped with invalid or occupant lifting and lengthwise shifting mechanism embodying my invention;

Figure 2 is a side elevational view of the equipped bed, illustrating the invalid or occupant moving or shifting mechanism of my attachments in lowered or so-called normal position in full lines and in raised or elevated or so-called abnormal position in dot-dash lines;

Figures 3 and 4 are fragmental longitudinal or horizontal sectional views of the equipped bed taken approximately on the lines 3—3 and 4—4, respectively, Figure 1;

Figure 5 is a longitudinal sectional view of the bed taken approximately on the line 5—5, Figure 2;

Figures 6, 7, and 8 are transverse or vertical sectional views of the equipped bed taken approximately on the lines 6—6, 7—7, and 8—8, respectively, Figure 2;

Figure 9 is a perspective view of the device in upright position beneath a hospital bed, the latter being shown in dotted lines; and

Figure 10 is a fragmental view of the device in collapsed position.

Referring now in more detail and by reference characters to the drawings, which illustrate a preferred embodiment of my invention, A designates a bedstead proper, which may be of any standard or approved form or type, which is preferably, as shown, of rectangular oblong configuration, and which includes head-uprights or posts 1, 1, and foot-uprights or posts 2, 2, rigidly joined in spaced parallel relation by a main frame *a* comprising head and foot cross-rails

3, 3, and longitudinally extending side rails 4, 4, all preferably of angular section, and a body-member in the form preferably for coolness and ventilation of a reticulated sheet or section 5 suitably marginally fixed to and resting upon the rails 3, 4.

The attachment comprises a supplemental frame B, which is of rectangular form and reduced dimensions relatively to the bedstead A and its frame *a*, and which includes longitudinally extending angle-members 6, joined to which are transverse or lateral angle-members 7, the frame B being in practice disposed under, and by means of spacing members 8 and threaded studs 9 or the like engaging the main frame-members 4 and supplemental frame-members 6 preferably detachably secured to, the main frame *a*, with the opposite side members 6 in registration with the opposite side members 4, 20 all as best seen in Figures 1, 5, and 6.

Integral with or otherwise fixed to, and depending from, each of the supplemental frame-members 6, are shaft hangers 10, as best seen in Figure 7. Rotatably mounted in, and extending horizontally through, the shaft hangers 10, are tubular shafts or so-called quills 11, each provided internally with a co-axial, rotatable solid shaft 12 projecting outwardly on both ends from the quill 11. Fixed upon the projecting ends of the shaft 12 are suitable pinions 13, for purposes presently appearing and as best seen in Figure 5.

C, C, designate what I will term post-frames, which are arranged in opposed relation upon opposite sides of the main frame *a*, and each having a cross-member *c* integrally provided with two spaced pairs of upstanding ears 14 disposed upon opposite sides of respective hangars 10 and swingably mounted upon a quill 11. In between each pair of ears 14, the upper edge of the cross-member *c* is provided with a flat machined abutment face 15 for engagement against a corresponding abutment shoulder 15' formed on the under side of each hangar 10, as best seen in Figure 7, for limiting the swingable movement of the latter to upright position or, as more fully presently appears, to a position in which its post-members *d* are upstandingly disposed at right angles to the respective frames *a* and B and in approximate parallel relation with the head and foot posts 1 and 2, as best seen in Figure 2. Of course, the frame C can be freely swung inwardly under the frames *a* and B to normal position, when the post-members *d* ex-

tend in parallel relation to such frames *a* and *B*, as indicated in dot-dash lines in Figure 7.

Fixed on each shaft *12* intermediate the respective quills *11*, is a tubular member *18*, fixed upon which is a miter gear *19*, and having meshing engagement with the gears *19* are miter gears *20* fixed on the respective opposite ends of a jack-shaft *21* extending transversely of the frames *a* and *B* and journaled for rotation on suitable hangers or brackets *22*, *22'*, depending from the respective frame-members *6*, as best seen in Figure 5.

Telescopically fitting for adjustment or extension in the tubular post-members *d*, are preferably tubular companion post-members or extensions *e*, provided longitudinally in the wall of which and presented toward the longitudinal frame-members *4* and *6*, are racks *23*, with which the pinions *13* have meshing engagement. The post-extensions *e* of each post-frame *C* have registering or aligning through-openings, as at *24*, at or adjacent their respective upper ends for shiftably accommodating for longitudinal movement a suitably elongated bar or shaft *D* provided suitably intermediate its ends and upon its inner face, for purposes presently appearing, with a rack *25* of selected length, and loosely sleeved on, and supported transversely of and over the main frame *a* by, the bars or shafts *D* of the companion post-frames *C*, are somewhat slack flexible invalid or occupant supporting straps or the like *E*.

The hanger *22'* is equipped with a pair of laterally presented parallel ears *26* providing a journal or bearing for the inner end of a shaft *27*, and fixed on the jack-shaft *21* intermediate the ears *26*, is a gear *28*, with which meshes a worm *29* fixed on the shaft *27* also intermediate the bracket ears *26*, as best seen in Figure 5, the shaft *27* being also suitably supported for rotation, as at *30*, on the frame *B* and by a bearing-bracket *31* fixed on the bedstead *A*.

Also journaled, as at *32*, on the bedstead *A*, is a crank *33* provided with a suitable gear *34* meshing with a second gear *35* fixed on the adjacent end of the shaft *27*.

Hence, assuming that the post-frames *C* are in abnormal position with their post-members *d* at right angles to the frames *a* and *B*, it will be evident that, on actuation of the crank *33*, rotary movement will be transmitted through the meshing gears *34*, *35*, to the shaft *27*, then by means of the meshing worm *29* and gear *28* to the jack-shaft *21*, and then by means of the meshing sets of miter gears *19* and *20* to the respective shafts *12* and their carried pinions *13*, such movement of the latter being translated through and by their engagement with the racks *23* for effecting reciprocatory travel of the post-extensions *e* relatively to the main frame *a* for correspondingly through or by means of their carried straps *E* raising or lowering the person or invalid relatively to the bedstead *A* for any desired ministrations.

Suitably conjoined or fixed to and extending in parallel relation with a tubular post-member *d* of each post-frame *C*, is a suitably elongated sleeve *36*, and also fixed to said member *d* adjacent its upper end and extending angularly therefrom over the open upper end of the respective sleeve *36*, is an arm *37*, rotatably mounted in the respective free ends of which is a quill *38*, and fixed, in turn, upon the upper end of the quill *38*, is a suitably axially apertured gear *39*.

Also extending obliquely from the upper end of

the post-extension *e* companion to said one post-member *d* in approximate alignment with the arm *37*, is a second arm *40*, and journaled at its upper end in the arm *40* and depending therefrom for slidable movement through the gear *39* and its supporting quill *38* and in the sleeve *36*, is a shaft *41*, fixed upon which is a suitable gear *42* having meshing engagement with the rack *25* of the respective post-frame *C*. As shown, each shaft *41* has a suitable head, as at *41'*, upon its upper end for shaft-supporting engagement with the respective arm *40*, and, as best seen in Figure 2, the shaft *41* has a key or feather connection with the quill *38* and gear *39* for effecting rotatory movement of the shaft *41* on rotatory movement of the gear or pinion *39*.

Depending from the frame *B*, is an aligning series of hangers *43*, supporting for rotation a transversely extending shaft *44* provided at its opposite ends with suitable gears *45* which mesh with the gears *39* supported on the quills *38*.

Fixed on the shaft *44* intermediate its ends, is a bevel gear *46*, which has meshing engagement with a companion gear *47* fixed on the adjacent end of a second crank-shaft *48* mounted for rotation in suitable bearings *49* supported respectively on the frames *B* and *a*, as best seen in Figure 5.

Hence, it will be evident that, on rotary actuation of the crank-shaft *48* in one or the other direction, the shaft *44* will be correspondingly rotarily actuated through and by means of the meshing gears *46*, *47*, and such rotary motion transmitted to and by the meshing gears *45*, *39*, to the rod or shaft *41* and from said shaft or rod *41*, in turn, to the pinion *42*, and such movement of the latter through the rack *25* effecting reciprocatory longitudinal movement of the shafts *D* and their supported straps *E* with respect to the bedstead *A* for correspondingly shifting the patient or occupant longitudinally for facilitating any desired ministration.

It will be noted that the shaft *44* is preferably somewhat obliquely disposed with respect to the frame *B* for gear-meshing engagement with the respective post-members *C*, necessitated by a slightly staggered relation between the members *C*, as best seen in Figure 1, for enabling compact nesting of said members when in normal position under the frames *a* and *B*. Preferably each post-frame *C* has a hinged rule-joint strap-connection, as at *50*, with the frame *B*, whereby the post-frames *C*, when the extensions *e* are in contracted position within the tubular posts *d*, may be readily shifted to position under the frame *B* and their swingable movement to upright position limited, the weight of the bed-occupant exerting, through the straps *E*, sufficient pull upon the frames *C* for maintaining the same in extended or abnormal position when in use, the co-operable gearing remaining or continuing in meshing engagement during and throughout disposition of the post-frames *C* either in, or while being swung to, normal or abnormal position. It is obvious that the attachment may be easily and quickly installed upon the particular bed and is exceedingly efficient in the performance of its intended functions.

It should be understood that changes and modifications in the form, construction, arrangement, and combination of the several parts of the structure may be made and substituted for those herein shown and described without departing from the nature and principle of my invention.

Having thus described my invention, what I

claim and desire to secure by Letters Patent is:

1. The combination with a hospital bed having side rails and end rails of a collapsible patient elevator mechanism comprising a supplemental frame disposed transversely of said bed and secured to the side rails thereof, hangers depending from said supplemental frame and extending outwardly of each of said side rails, a pair of post frames hingedly connected respectively to the hangers adjacent each side rail for movement optionally into collapsed position underneath said supplemental frame or into upstanding position on opposite sides of said hospital bed outwardly of said side rails, stop means limiting the movement of said post frames to upright position, each post frame including a pair of spaced parallel tubular posts, companion members telescopically fitting within the posts, each of said members having a longitudinally extending rack, bars supported by the respective pairs of members for disposition longitudinally upon opposite sides of the bedstead, straps supported by the bars for slackwise disposition transversely over the bedstead, and means comprising shafts mounted for rotation in the hangers and gears fixed on said shafts and engaging said racks for, when the post frames and their posts are in upstanding position upon opposite sides of the bedstead, shifting said members for raising or lowering said straps relatively to the bedstead.

2. The combination with a hospital bed having side rails and end rails of a collapsible patient elevator comprising a supplemental frame disposed transversely of said bed and secured to the side rails thereof, said supplemental frame having portions extending outwardly of each side rail, longitudinally extending quills rotatably mounted in suitable openings of the extending portions, a pair of post frames hingedly mounted on said quills adjacent each side rail for movement optionally into collapsed position underneath said supplemental frame or into upstanding position on opposite sides of said hospital bed outwardly of said side rails, stop means limiting the movement of said post frames to upright position, each post frame including a pair of spaced parallel tubular posts, companion members telescopically fitting within the posts and provided with longitudinally extending racks, bars supported by the respective pairs of members for disposition longitudinally upon opposite sides of the bedstead, straps supported by the bars for slackwise disposition transversely over the bedstead, and means comprising shafts mounted for rotation in the quills and gears fixed on said shafts and engaging said racks when the post frames and their posts are in upstanding position upon opposite sides of the bedstead, for shifting said members for raising or lowering said straps relatively to the bedstead.

3. The combination with a hospital bed having side rails and end rails of a collapsible patient elevator mechanism comprising a supplemental frame disposed transversely of said bed and secured to the side rails thereof, said supplemental frame having portions extending outwardly of each side rail, a pair of post frames hingedly connected respectively to the extending portions adjacent each side rail for movement optionally into collapsed position underneath said supplemental frame or into upstanding position on opposite sides of said hospital bed outwardly of said side rails, means optionally holding said post frames in upright position, each post frame including a pair of spaced parallel

tubular posts, bars supported by the respective pairs of posts for shiftable disposition longitudinally upon opposite sides of the bedstead, straps supported by the bars for disposition transversely over the bedstead, and means for shifting said bars and their supported straps longitudinally with respect to the bedstead.

4. The combination with a hospital bed having side rails and end rails of a collapsible patient elevator mechanism comprising a supplemental frame disposed transversely of said bed and secured to the side rails thereof, hangers depending from said supplemental frame and extending outwardly of each of said side rails, a pair of post frames hingedly connected respectively to the hangers adjacent each side rail for movement optionally into collapsed position underneath said supplemental frame or into upstanding position on opposite sides of said hospital bed outwardly of said side rails, stop means limiting the movement of said post frames to upright position, each post frame including a pair of spaced parallel tubular posts, bars supported by the respective pairs of posts for shiftable disposition longitudinally upon opposite sides of the bedstead, straps supported by the bars for disposition transversely over the bedstead, longitudinal racks on said bars, shafts rotatably carried by each post frame, gears on said shafts meshing with said racks, and means for rotarily actuating said shafts for shifting said bars and their supported straps longitudinally with respect to the bedstead.

5. The combination with a hospital bed having side rails and end rails of a collapsible patient elevator mechanism comprising a supplemental frame disposed transversely of said bed and secured to the side rails thereof, hangers depending from said supplemental frame and extending outwardly of each of said side rails, a pair of post frames hingedly connected respectively to the hangers adjacent each side rail for movement optionally into collapsed position underneath said supplemental frame or into upstanding position on opposite sides of said hospital bed outwardly of said side rails, stop means limiting the movement of said post frames to upright position, each post frame including a pair of spaced parallel tubular posts, companion members telescopically fitting within the posts, bars supported by the respective pairs of members for shiftable disposition longitudinally upon opposite sides of the bedstead, straps supported by the bars for disposition transversely over the bedstead, means for shifting said members for raising or lowering the straps relatively to the bedstead, and means for shifting said bars and their supported straps longitudinally of the bedstead.

6. The combination with a hospital bed having side rails and end rails of a collapsible patient elevator mechanism comprising a supplemental frame disposed transversely of said bed and secured to the side rails thereof, hangers depending from said supplemental frame and extending outwardly of each of said side rails, a pair of post frames hingedly connected respectively to the hangers adjacent each side rail for movement optionally into collapsed position underneath said supplemental frame or into upstanding position on opposite sides of said hospital bed outwardly of said side rails, stop means limiting the movement of said post frames to upright position, each post frame including a pair of spaced parallel tubular posts, companion

members telescopically fitting within the posts, each said member having a longitudinally extending rack, bars supported by the respective pairs of members for shiftable disposition longitudinally upon opposite sides of the bedstead, each bar having a longitudinally extending rack, straps supported by the bars transversely over the bedstead, means comprising shafts mounted for rotation in said hangers and gears fixed on said shafts and engaging the racks of said members for shifting the same for raising or lowering said bars and straps relatively to the bedstead, and means for shifting said bars and straps longitudinally of the bedstead, said last means including sleeves conjoined to the posts, shafts shiftable with respect to the sleeves, co-operable gears for rotatably actuating said shafts, and gears on the shafts meshing with said bar-racks.

7. The combination with a hospital bed having side rails and end rails of a collapsible patient elevator comprising a supplemental frame disposed transversely of said bed and secured to the side rails thereof, said supplemental frame having portions extending outwardly of each side rail, longitudinally extending quills rotatably mounted in suitable openings of the extending portions, a pair of post frames hingedly mounted on said quills adjacent each side rail for movement optionally into collapsed position under-

neath said supplemental frame or into upstanding position on opposite sides of said hospital bed outwardly of said side rails, stop means limiting the movement of said post frames to upright position, each post frame including a pair of spaced parallel tubular posts, companion members telescopically fitting within the posts, each said member having a longitudinally extending rack, bars supported by the respective pairs of members for shiftable disposition longitudinally upon opposite sides of the bedstead, straps slackwise supported by the bars transversely over the bedstead, means comprising shafts mounted for rotation in the quills and gears fixed on said shafts and engaging said racks when the second frames and their posts are in upstanding position upon opposite sides of the bedstead, for shifting said members for raising or lowering said bars and their supported straps relatively to the bedstead, and means for shifting said bars and straps longitudinally of the bedstead also when the posts are in upstanding position, said last means including sleeves conjoined to the posts, shafts vertically shiftable with respect to the sleeves, gear means for rotatably actuating the shafts, and gears on the shafts meshing with said bar-racks.

ALBERT L. BRESCH.
